Jacob Kautz.
INVENTOR
BY Victor J. Evans
ATTORNEY

UNITED STATES PATENT OFFICE

JACOB KAUTZ, OF CHICAGO, ILLINOIS

OVERALLS

Application filed October 31, 1928. Serial No. 316,177.

This invention relates to certain novel improvements in overalls, and has for its principal object the provision of an improved construction of this character which will be 5 arranged in an advantageous manner and which will be economical in manufacture.

The salient object of my invention is to provide a mechanic's overall which will be so arranged that pockets will be provided at 10 expeditious points to facilitate the carrying of tools and other appurtenances so that they will be readily accessible when use thereof is desired.

Another object of the invention is to provide a device of the above named character which will have a plurality of pockets provided thereon so arranged that they may be held in determined positions or so that portions thereof may be permitted to swing free 20 from the main body portion.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a front elevational view of a preferred form of construction for my improved overall;

Fig. 2 is a rear elevational view of the overall illustrated in Fig. 1;

Fig. 3 is a fragmental detail view depicting a portion of the rear of the overall arranged in a manner somewhat different from that illustrated in Fig. 2; and

Fig. 4 is a fragmental detail view substantially similar to Fig. 1 depicting a modified form of construction.

In the accompanying drawings wherein I have illustrated a preferred form of construction for my device 10 indicates the bib portion of my improved overall which is 45 formed of two sections 11 and 12 that are joined at substantially the mid-portion of the bib by suitable stitching as indicated at 13. The overall also comprises leg portions 14 and 15 which are joined together to provide a crotch 16 and which have portions that

extend above the crotch and which on the front side of the overall are joined to the lower end of the sections 11 and 12 forming the bib portion 10. At the upper end of the rear side of the leg portions the strap members 17 and 18 are secured which are crossed as at 19. At the free ends of the strap portions suitable connecting elements 20 are provided which co-operate with connecting elements 21 provided on the upper end of the bib portion 10. Suitable adjustment members 22 are provided in the strap member 17 and 18 adjacent the connecting elements 20 in order that the length of the strap members may be varied. The limb portions 14 and 15 along the outer edges thereof above the plane of the crotch 16 are open and are held together by suitable button and button hole structures 23 for purposes well understood in the art. The foregoing describes the manner in which standard overalls are formed and my improved construction while preferably associated with an overall constructed along lines just set forth it is not limited to this construction since my improved pocket structure may be used in association with any desired type of construction.

On the bib construction 10 I provide a pocket 24 which is divided into two compartments 25 and 26, the pocket 26 being of less width than the pocket 25. Secured on the bib 10 adjacent the pocket 24 is another pocket 27. These pockets may be employed for a number of purposes such as; for example, the carrying of a collapsible scale and a pencil and other appurtenances.

Secured so as to have the upper edge thereof fastened to the point juncture between the lower edge of the bib and the upper ends of the leg members is an apron member 28. Inasmuch as only the upper edge of the apron member is secured I arrange two strap members 29 on the lower end of the apron member which extend outwardly therefrom and which have button holes provided therein that co-operate with the button members 30 to fasten the lower edge portion of the apron member in a detachable manner. On the apron member 28 I provide three pockets 31, 32, and 33. These last named pockets may be employed

for the carrying of nails or other analogous devices and it is apparent by the detachable connection for the lower edge of the apron construction that these nails or other analogous devices will be suspended free from the worker's body rather than be fixedly secured thereto which would tend to be uncomfortable to the wearer when bending into a stooping position. It is apparent that when the wearer bends forwardly at his waist the apron construction will swing forwardly from engagement with the main body portion, the advantage of which is readily apparent.

Below the lower edge of the apron member 15 I provide on the leg members 14 and 15 two pockets 30a which may be employed to carry anything desired by the mechanic as, for example, securing devices such as nails and so forth, or which may be employed for the carrying of small tools such as screw drivers and wrenches.

If desired a suitable pocket may be provided on the bib member 10 of relatively large size and this pocket may be provided either 25 on the inner or the outer side thereof. The utility of this pocket is that, when the overall is worn by a paper hanger, a convenient pocket will be provided intended to receive his brush. However, for the purpose of clarity I have omitted the disclosure of this 30 pocket from the drawings since it is believed that the installation thereof will be readily understood.

On the lower portion of the leg member 14 35 I provide a pocket structure 34. This pocket structure is intended to serve as a receptacle for nails or similar devices. When the overall is worn by a man laying flooring access to these nails may be readily attained if they 40 are mounted in this pocket 34 since a new nail may be secured without the necessity of the user straightening up to facilitate the extraction of a nail from one of the pockets 31, 32, or 33. On the sides of the leg members 14 and 45 15 I provide suitable loop members 35. These loop members may be employed for carrying tools such as wrenches or claw hammers as is well understood in the art.

Provided on the rear side of the overall 50 below the point at which the strap members 17 and 18 are secured and on the rear side of the leg members 14 and 15 are two pockets 36 and 37. A suitable loop member 38 co-operates with the pocket 36 as illustrated in Fig. 55 2 and serves as a support for a wrench or the like. Mounted above the pockets 36 and 37 in a manner such that only the rear side at the upper edge thereof is secured are two sack or pocket members 39 and 40 which under 60 normal conditions may be disposed interiorly of the pockets 36 and 37. These pockets are replaceable and may therefore be used for the carrying of heavy tools and the like and further by providing two co-operating pockets 65 so that the segregation of the tools may be

better carried out. However, I have also arranged these pockets so that they may be disposed to extend over the pockets 36 and 37 and in order to retain them in this position I provide strap elements such as that indicated by 41 in Fig. 3 which has a button hole provided therein that co-operates with the button 42 to lock these pockets in position. With the pockets mounted, exteriorly of the overall in this manner the same may be held 70 in position and at the same time afford greater flexibility to the wearer of the overall.

Mounted below the pocket 37 on the rear side of the leg member 15 is a small pocket 43 which may be employed for the carrying of a collapsible scale or other suitable rule or if desired a so-called tri-square may be carried in this pocket.

In Fig. 4 I have depicted a modified form of construction for the bib portion of my improved overall. In this instance the bib 10 is formed in two sections 11 and 12 in a manner substantially similar to that set forth hereinto and are joined by suitable stitching indicated by 13. On the inner surface of the sections 11 and 12 I provide two relatively large pockets indicated by 43 and 44. This particular pocket arrangement is particularly advantageous for the use of painters, paper hangers and similar mechanics since it affords a pocket structure into which the brush and similar tools employed by such mechanics may be inserted.

It is apparent from the foregoing description that I have provided an overall embodying an advantageous pocket structure having pockets located at proper points to best permit the carrying of a mechanic's tools and other appurtenances. While in the previous description I have described button and button holes as being used as the fastening elements I wish it to be distinctly understood that this is not to be taken as a limitation of my invention for other analogous securing devices might be substituted in place of these buttons and button holes without departing from the purview of my invention.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claim.

Having thus described my invention what I claim is new and desire to protect by Letters Patent is:

In an overall, the combination of a stationary pocket adjacent the upper end of the leg portion of the garment on the rear side thereof and having an open upper end, a swinging pocket stitched to the garment

above the open upper end of said stationary pocket and insertible therewithin, a connecting element on the leg portion below the stationary pocket, a tab depending from the 5 lower end of the swinging pocket, a connecting element on said tab adapted to be connected to said first named element whereby said swinging pocket may serve as a flap for said stationary pocket, and loops extended 10 around the side of the leg to provide tool supports, said loops having the front ends thereof secured to the front side of the leg portion and having the rear ends thereof disposed between said stationary pocket and the leg portion 15 and stitched thereto at the outer seam line of said stationary pocket whereby to reinforce said loops.

In testimony whereof I affix my signature.
JACOB KAUTZ.
